United States Patent Office

Des. 229,824

Patented Jan. 8, 1974

229,824

BASE FOR A CONTAINER

Herbert R. Erickson, Denver, Colo., assignor to Best Quality Plastics, Inc., Denver, Colo.

Filed Feb. 3, 1972, Ser. No. 223,400

Term of patent 14 years

Int. Cl. D9—03

U.S. Cl. D9—219

Fig. 1

Fig. 2

Fig. 3

FIG. 1 is an elevational view of a base for a container showing my new design.

FIG. 2 is a plan view; and

FIG. 3 is a sectional view taken on the line 3—3 of FIG. 2.

I claim:

The ornamental design for a base for a container, as shown.
